(57) **CLAIM**

The ornamental design for an on-hand attachment band, as shown and described.

DESCRIPTION

FIG. 1 is a top perspective view of an on-hand attachment band shown in an environment of use;

FIG. 2 is a top and front perspective view thereof;

FIG. 3 is a top plan view thereof;

FIG. 4 is a bottom plan view thereof;

FIG. 5 is a front elevational view thereof;

FIG. 5 is a rear elevational view thereof;

FIG. 6 is a rear elevational view thereof;

FIG. 7 is a right side elevational view thereof; and,

FIG. 8 is a left side elevational view thereof.

The broken lines showing a hand in FIG. 1 represent environment. The remaining evenly spaced broken lines shown in FIGS. 1-8 illustrate portions of the on-hand attachment band which form no part of the claimed design.
